UNITED STATES PATENT OFFICE

SPENCER JOHN TUCKER, OF JAMAICA, NEW YORK, ASSIGNOR TO EDWD. F. CALDWELL & CO. INC., OF NEW YORK, N. Y., A CORPORATION OF NEW YORK

DESIGN FOR A LIGHTING FIXTURE

Application filed July 19, 1932. Serial No. 44,379. Term of patent 7 years

To all whom it may concern:

Be it known that I, SPENCER JOHN TUCKER, a subject of the King of Great Britain, and a resident of Jamaica, borough of Queens, in the county of Queens, city and State of New York, have invented the new, original, and ornamental Design for a Lighting Fixture, of which the following is a specification.

Reference is had to the accompanying drawing forming a part hereof, in which

The lighting fixture has an annular member extending outwardly and upwardly from the periphery at the top of a depending hemispherical bowl.

I claim:

The ornamental design for a lighting fixture as shown and described.

SPENCER JOHN TUCKER.
